UNITED STATES PATENT OFFICE.

BENJAMIN M. TAKAHASHI, OF HARLOWTON, MONTANA.

LENS-SHIELDING ATTACHMENT FOR CAMERAS.

1,283,963.

Specification of Letters Patent.

Patented Nov. 5, 1918.

Application filed May 20, 1918. Serial No. 235,865.

To all whom it may concern:

Be it known that I, BENJAMIN M. TAKAHASHI, a subject of the Emperor of Japan, and a resident of Harlowton, in the county 5 of Wheatland and State of Montana, have made certain new and useful Improvements in Lens-Shielding Attachments for Cameras, of which the following is a specification.

My present invention relates generally to 10 cameras, and particularly to certain improvements in lens shielding attachments therefor in connection with the device described and claimed in my Patent 1,262,187 granted April 9, 1918, the primary object 15 of my present improvements being the provision of a lens shielding attachment by means of which a lens may be conveniently shielded either with or without a ray filter, and the latter conveniently carried and 20 fully protected in use.

In the accompanying drawing illustrating my present improvements:—

Figure 1 is a side view of the attachment;

Fig. 2 is a sectional view therethrough with the shielding disk and filter cover open;

Fig. 3 is a similar view with the shielding disk and filter cover closed;

Fig. 4 is a horizontal section taken substantially on line 7—7 of Fig. 3.

Referring now to these figures, the lens shield of my present invention as in my patent above referred to, is in the form of a shielding disk 10 which is hinged at one 35 point to an adjusting ring 11, having an inner annular groove receiving the annular rib 12 at one end of a cylindrical holder 13, the opposite end of which has an annular series of longitudinal slots 14, whereby to 40 adapt the same to telescope upon and frictionally engage the lens barrel of a camera of any suitable type.

The lens shielding disk 10, which is opaque and has its annular edge provided 45 with a rounded flange 15, is thus adapted for movement upon its hinge 16 from the position at right angles to the axis of the cylindrical holder 13, and as seen in Fig. 3, to a position more or less parallel to the axis 50 of the cylindrical holder, as seen in Fig. 2, the latter being the operative position wherein the disk 10 will operate to intercept glaring light reflections and the like which would otherwise distribute themselves unevenly upon a film or plate to the

detriment of the photographed image or scene.

In its position as shown in Fig. 3, which is the position of disuse, the disk 10 operates to entirely close the outer end of the cylindrical holder 13, so that it prevents the entrance of dust, dirt, moisture and the like, the adjusting ring 11 having an extending lip 17 at a point diametrically opposite the hinge 16, and for engagement with the flanged edge of the disk 10 to hold the latter in closed position. The flanged edge of the disk 10 is also provided with a finger piece 18, by which it may be conveniently released from the clamping lip 17 when it is to be 60 opened for use.

The wall of the adjusting ring 11 outwardly beyond the cylindrical holder 13, has an intermediate annular rib 19 within which a ray filter in the form of a filtering disk 20 may be seated, this filter being of any suitable material and color for the particular purpose for which it is to be used.

An apertured cover plate 21 having an annular flanged edge 22 and of reduced 75 diameter as compared to that of the shielding disk 10 is hinged at 23 upon the outer portion of the adjusting ring 11 adjacent to the hinge 16, of the disk 10, the diameter of this plate being such that its flanged 80 edge will clasp around the rib 19 in the closed position shown in Fig. 3, so as to thereby engage a portion of the outer surface of the ray filter 20, and effectively support the latter against the outer face of the 85 adjusting ring.

It will be noted from Fig. 3 in particular that the opening 24 of disk 21 is of a diameter substantially the same as the inner diameter of the outer portion of the adjust- 90 ing ring.

Thus by the use of my improved shielding attachment the extreme high lights, sea-shore reflections, and the like may be cut off through the use of the shielding disk 10 either with or without a ray filter 20, the latter of which is, when used, held firmly in position by the cover plate 21; in such manner, however, that it may be readily removed for the substitution of a filter more 105 or less dense, or one of a different color.

It is obvious that by virtue of the annular adjustment of the ring 11, with respect to the cylindrical support 13 engaging the lens barrel, the shielding disk 10 may be 110

annularly adjusted with respect to the lens barrel so as to intercept rays in no matter which direction they may approach.

I claim:-

- 5 1. A device of the character described consisting of a cylindrical holder for telescoping engagement upon a lens barrel, an annularly adjustable ring carried by the holder having means for detachably supporting a ray filter, and a lens shielding disk hinged to the said ring and acting as a cover for the same and the filter holding means when in closed position.
- 10 2. A device of the character described including a holder, an annularly adjustable ring carried by the holder, a lens shielding disk hinged to the outer portion of the said ring to open and close with respect thereto, and a ray filter detachably supported by the ring and covered by the said disk in the closed position of the latter.
- 15 3. A device of the character described in-

cluding a holder, an annularly adjustable ring carried by the holder and provided with an annular rib forming a support for a ray filter, an apertured cover plate hinged to the ring and movable into and out of clasping engagement with the said rib, and a lens shielding disk also hinged to the adjusting ring to close and open with respect thereto and forming a cover for the ray filter and the cover plate thereof when closed.

25 4. A device of the character described including a cylindrical support, a lens shield adjustable around the support and hinged to open and close, and filter supporting means adjacent the holder and normally covered by the shielding disk in the closed position of the latter.

30 BENJAMIN M. TAKAHASHI.
